UNITED STATES PATENT OFFICE

WALTER GLEDHILL, OF HUDDERSFIELD, ENGLAND

RISING-AND-FALLING SHUTTLE BOX AND LIKE MOTIONS FOR LOOMS FOR WEAVING

Application filed August 26, 1931, Serial No. 559,529, and in Great Britain October 9, 1930.

The invention relates to looms employing rising-and-falling shuttle box or equivalent motions, and although applicable to any looms having motions of this description it has particular reference to looms, employing stationary weft supplies, wherein a series of wefts of different colours or characters are associated with respective delivering grippers any one of which can, by vertical movement, be detachably connected to, or disconnected from, a horizontally moving carrier bar designed to carry its associated gripper part way across the shed, where such gripper hands over the end of its weft thread to a receiving gripper, which completes the laying of the weft in the shed. A loom of the construction referred to is described in the specification of my prior Patent No. 1,802,311.

It is found in practice that it is desirable to provide means to ensure the exact vertical positioning of the delivering grippers each time a change is to be made from one gripper to another in order that the box compartment containing the selected gripper may be presented truly in alignment with the carrier bar and the present invention has for its object to provide means to this end.

The invention is characterized in that the usual vertically-movable rod, by which the movable "box" or housing for the delivering grippers is actuated, has associated with it a series of surfaces adapted to co-operate with a fixed surface carried by the loom frame, so that in the event of the box not having been moved by its actuating means to the exact vertical level desired, the fixed surface will co-operate with the corresponding surface or surfaces on the box lifter rod and will move the box vertically into the correct position. The term "fixed" applied to the member carried by the loom frame refers to its vertical position, and said member will preferably be movable in a horizontal plane and be connected to the usual handle or part provided to enable the loom to be turned back by hand, so that when the loom is to be so turned, the box rod will be freed for the necessary vertical movement. Whilst re-instatement of normal conditions will ensure

that the box is correctly positioned before the loom is re-started.

In the accompanying drawing, Fig. 1 is a front view of an embodiment of the invention, and

Fig. 2 is a plan view of the vertically-fixed positioning member.

Referring to the drawing *a* represents the raceway of the loom, and *b* a "shuttle box", having a series of compartments *b'*, each adapted to receive a weft-carrier or gripper *c*, said box being movable vertically to bring a selected compartment opposite the raceway. Vertical movement of the box is adapted to detach one gripper from a horizontally movable carrier bar *d* and to effect the connection to said bar of the gripper which is moved into line with the raceway.

Vertical movement is given to the box by a rod *e* on which it is carried, said rod receiving rising and falling movements by suitable mechanism, not shown, under indication of a pattern mechanism.

The parts so far referred to form no part of the present invention, which relates solely to means for ensuring the accurate positioning of a selected compartment of the box in relation to the carrier bar and raceway, so that when the bar attempts to move inwardly, its movement is not obstructed by the box, neither is the inward movement of the gripper obstructed by the raceway.

In the illustrated embodiment of our invention the box rod is provided with a series of appropriately spaced rollers *f* mounted on horizontal axes, and pivoted at *g'* to the loom frame or to a bracket carried thereby, so as to swing in a horizontal plane, is a positioning member *g* in the form of a bar having a tapered or wedge-shaped engaging surface *g'* which, as the bar swings rearwardly is adapted to enter between an adjacent pair of the rollers *f* and, in the event of the rod *e* not having moved the box to the exact height required, will function to correct the position of the box.

The member *g* is appropriately curved to allow for the arcuate motion occasioned by the swing of the loom lay.

The vertical movement of the box *b*, if

called for by the pattern surface takes place during the time the lay is completing its forward or beat-up movement and is commencing its rearward movement. The projecting 5 portion g^3 of the member g , having at its front end the tapered surface g^2 is, therefore, so positioned that the said surface does not co-operate with a pair of rollers f until the lay reaches a position in its rearward 10 swing such that vertical movement of the box b by the rod e has been completed.

If the box is incorrectly positioned the entry of the surface g^2 between a pair of rollers corrects the positioning and during the remainder of the backward swing and the first 15 part of the next forward swing the projection g^3 remains between the rollers and preserves the correct positioning of the box.

It may be that, in order to correct irregularities or for other reasons it is desired to move the box b by hand when the lay is so far back that the projection g^3 is engaged between a pair of rollers. It is for this reason that the member g is mounted pivotally, to 25 swing in a horizontal plane. The front end of the member is guided in a slot in a bracket fixed on the loom frame, and it has a connection h to the usual handle controlling the disconnecting means between the dobby or 30 head motion of the loom, the box motion or means for giving vertical movements to the rod e , and the rest of the loom drive. When the handle referred to is operated to effect disconnection, the member g is swung outwardly, as indicated in dotted lines in Fig. 35 2 to a position in which it is clear of the rollers f , so that the box can be raised or lowered at any position of lay movement. When the handle is operated to re-connect the dobby 40 or head motion and the box motion, the member g is moved back so that the projection g^2 re-enters between the pair of rollers which may have been brought into position. It may be that the operation of the box rod 45 has not quite accurately positioned the box and the inner edge of the projection g^2 is therefore made of taper or wedge form as indicated at g^4 . Thus, when the member is swung inwardly the surface g^4 will correct 50 any imperfection in the positioning of the box.

Obviously, instead of the member g being mounted pivotally, it might be mounted to slide horizontally inwards and outwards relatively to the box rod, but the pivotal arrangement shown is preferred.

In order to avoid breakage such as might occur in the event of a change in the vertical position of the box being attempted at a time 60 when the positioning member was engaged between a pair of rollers f , or if for any other reason vertical movement of the box is obstructed, it is preferable to make the box rod in two parts united by a give-way connection. To this end the rod e may have slid-

able within its lower end a part e' and carry a pivoted latch i normally pressed by a spring j into a recess in the part e' . The part e' is connected to the box-operating means, and in the event of obstruction to vertical movement of the box the latch will become disengaged and the part e' will move idly within the part e . When the obstruction is removed, the latch will spring back into place and the parts e' and e will move together.

It will be obvious that the actual details of construction and arrangement of the parts employed may vary from those of the particular embodiment illustrated, whilst still retaining the essential feature of the invention, namely the provision on the box rod of surfaces adapted to cooperate with a vertically fixed positioning member designed to ensure the correct alignment of a compartment of the box in relation to the carrier bar and raceway.

It is a matter of some difficulty to adjust the ordinary box actuating mechanisms to give the required degree of accuracy, but the employment of means according to the invention obviates necessity for close adjustment of the actuating mechanism, since the latter is now only called upon to move the box rod to an approximate position, any necessary correction being effected by the co-operating surfaces.

It will be apparent that the invention can, with advantage, be applied to ordinary shuttle looms, using rising and falling shuttle boxes, since the correct positioning of the shuttle in relation to the picker will tend towards accuracy and smoothness of working.

Having thus described my invention, what I claim as new and desire to secure by Letters Patent is:—

1. In a weaving loom employing a rising-and-falling shuttle box or equivalent motion, a box having a series of superposed compartments, a rod carrying said box and adapted to be moved vertically under indication of a pattern-controlled mechanism, a series of vertically-spaced rollers on said rod, said rollers being rotatable about horizontal axes, and a vertically-fixed positioning bar member having a tapered engaging surface adapted to enter between adjacent pairs of rollers after the box-shifting mechanism has ceased to operate and by such entry to correct any irregularity in the vertical positioning of the box.

2. In a weaving loom employing a rising-and-falling shuttle box or equivalent motion, a box having a series of superposed compartments, a rod carrying said box and adapted to be moved vertically under indication of a pattern-controlled mechanism, a series of vertically spaced surfaces on such rod corresponding to various lifts of the box, a positioning member movable in a horizon-

tal plane and adapted to co-operate with the surfaces on the rod to correct any irregularity in the vertical positioning of the box, and means whereby when the box shifting mechanism is disconnected from the loom drive said positioning member is removed to an inoperative position.

3. In a weaving loom employing a rising-and-falling shuttle box or equivalent motion, 10 a box having a series of superposed compartments, a member carrying said box and adapted for vertical movement, spaced rotatable elements carried by said member, a movable positioning member adapted to enter between 15 adjacent pairs of the rotatable elements to correct any irregularity in the vertical positioning of the box, and means whereby when the box shifting mechanism is disconnected from the loom drive said positioning member 20 is removed to an inoperative position.

4. In a weaving loom employing a rising-and-falling shuttle box or equivalent motion, a box having a series of superposed compartments, a box carrying member connected 25 to operating means and adapted for vertical positioning movement, a series of vertically spaced surfaces on said member, a movable positioning member adapted to cooperate with the surfaces on the member to correct 30 any irregularity in the vertical positioning of the box, a slidable member arranged within the lower portion of said box carrying member and connected to the box operating means, means pivotally connected 35 to said box carrying member and normally engaging and locking said slidable member against movement within said member, and means whereby said slidable member may be released from its locking engagement for 40 idle movement within the box carrying member whereby the box is held in an inoperative position.

5. In a weaving loom employing a rising-and-falling shuttle box or equivalent motion, 45 a box having a series of superposed compartments, a box carrying member connected to operating means and adapted for vertical positioning movement, a series of vertically spaced surfaces on said member, a movable 50 positioning member adapted to cooperate with the surfaces on the member to correct any irregularity in the vertical positioning of the box, a slidable member carried by said box carrying member and normally in 55 locking engagement therewith, said slidable member connected to the box operating means, and means whereby said slidable member may be released from its locking engagement for idle movement whereby said box 60 is held in inoperative position.

In testimony whereof I affix my signature.
WALTER GLEEDHILL.
